UNITED STATES PATENT OFFICE.

JAMES E. GAUSE, OF BROWNSVILLE, TENNESSEE.

WATCH-RACK.

SPECIFICATION forming part of Letters Patent No. 358,193, dated February 22, 1887.

Application filed March 3, 1886. Serial No. 193,870. (No model.)

To all whom it may concern:

Be it known that I, JAMES E. GAUSE, of Brownsville, in the county of Haywood and State of Tennessee, have invented a new and 5 Improved Watch-Rack, of which the following is a full, clear, and exact description.

My invention relates to racks adapted especially for the use of watch-makers and jewelers for hanging watches and jewelry upon, 10 and has for its object to provide an inexpensive and neat rack, which may readily be folded or rolled up, with the articles held by it, for placing the goods with the rack in a safe over night, and may be as readily unfolded and hung up to display the articles, 15 whereby time and labor will be saved in handling the goods. The rack may also be used as a fixed or stationary rack for displaying a variety of merchandise.

20 The invention consists in certain novel features of construction and combinations of parts of the rack, all as hereinafter described and claimed.

Reference is to be had to the accompanying 25 drawings, forming a part of this specification, in which similar letters of reference indicate corresponding parts in both the figures.

Figure 1 is a front view of the watch-rack as supported from a frame of metal rods, and 30 Fig. 2 is an enlarged perspective view of one of the rack-hooks and parts of the chains by which it is held drawn to a larger scale.

The watch-rack consists of a backing or groundwork of some suitable flexible material adapted to be readily folded or rolled up, 35 and a series of hooks attached thereto to receive the watches, lockets, or other articles of jewelry.

The hooks A of the rack are connected by 40 loops or eyes a a, formed at their opposite ends, with the cross-bars b b of wire frames B, which frames have a general rectangular form with side bars, b' b', slightly curved outward, and provided, preferably, with corner bends 45 or loops, b'', as clearly shown in Fig. 2, and to which loops the ends of short connecting chains or cords C are attached, to hold the hooks and frames A B by and between the chains in a net-like and flexible structure, as 50 in Fig. 1.

One side, a', of the rack-hook A is made continuous and concaved rearward, and the

front portion of the hook is formed in an upper part, a'', curving downward and outward from the upper eye, a, of the hook, and at the 55 end of part a'' the elastic metal of the hook is bent downward and backward to form a part or lip, a'', the lower end of which preferably rests against and is adapted to slide on the rear side, a', of the hook. The lower part, a'', 60 of the front of the hook extends upward from the lower eye, a, in concavo-convex form about to the point of junction or the bend between the parts a'' a'', thus providing a slit or space at D, through which the rings e of watches or 65 lockets E may be passed to suspend them from the hooks, as shown in Fig. 1.

In placing the watches or lockets E in the hooks A their rings e will be pressed against the parts a'' of the hooks, which will yield 70 backward as the ends of parts a'' slide on the rear sides, a', of the hooks, and whereby the slit or slot at D will be opened sufficiently to allow the ring e to enter the hook, and when the watch is to be removed from the hook its 75 ring e will be lifted up between the parts a'' a'' of the hook, and may be drawn through the slit at D as the lower front part, a'', of the hook springs outward at its upper end. A slight twisting or turning movement of the watch 80 or other article will facilitate its removal from the hook. After the watches E or other articles are hung on the hooks they will not accidentally become disengaged therefrom. Consequently the entire rack, with the articles held 85 by it, may be folded up and placed in a drawer or safe over night, and may again be unfolded and hung up, without danger of losing the watches or other articles from it, and whereby time is economized over the method of hanging each article on a separate open hook and removing it therefrom for safety over night. The shape of the hooks A is such that the chains C or the articles held by the hooks cannot enter or catch on the hooks or become 95 entangled; hence the rack will always unfold quickly and easily.

The rack may be hung from nails driven into a wall or counter, or into cross-bar of a sash or show-window or other support.

I show the rack hung from a frame of metal or other ornamental rods, consisting of a head-piece, F, supported by opposite side rods, G G, which may be attached directly to the floor of

a show-window, or to a base-piece, H. Open hooks A' are fixed to the top row of hooks A, as indicated in dotted lines in Fig. 2, said hooks A' being engaged with the head-piece F, to 5 suspend the rack therefrom.

Spiral springs I, connected to the lower outside hook-frames, B B, of the rack, and to eyes g g on the posts G G, draw on the rack to hold it tightly stretched between the posts. Rubber bands or tie-chains may be used instead of 10 the springs I, if preferred.

The chains C may be substituted by a flexible fabric of any kind—such as velvet, plush, silk, or other suitable material—which will 15 fold readily, and to which the hook-frames may be attached.

Having thus fully described my invention, I claim as new and desire to secure by Letters Patent—

20 1. A watch-rack made of a backing or network of flexible material, and hooks fixed thereto, adapted to receive and retain the watches or other articles hung thereon when the flexible backing is folded and unfolded, substantially as herein set forth.

25 2. The combination, in a watch-rack, of hooks adapted to receive watches or other articles, frames B, to which the hooks are connected, and chains C, connected to the hook-frames to 30 form a flexible rack, substantially as herein set forth.

35 3. A rack hook and support comprising a hook, A, adapted to receive watches or other articles, and provided with end loops or eyes, a a, and a frame, B, consisting of opposite side bars, b b', connecting the bars b b, substantially as herein set forth.

4. In watch-racks, the hook A, formed with a rear side or part, a', an outbent front part,

a', an inbent part, a', connected to part a', 40 and inclining downward and backward, and a lower front part, a', providing a slit, as at D, in combination with a flexible webbing or backing, substantially as and for the purposes herein set forth.

45 5. In watch-racks, the hook A, formed with opposite end loops, a a, a rear part, a', and front part, a', an inbent part, a', connected to part a' and inclining downward and backward, and a lower front part, a', providing a 50 slit, as at D, in combination with a frame, B, made with end bars, b b, on which the hook-loops a a are fitted, opposite side bars, b b', and a flexible webbing or backing, substantially as and for the purposes herein set forth. 55

6. In watch-racks, the combination of hooks A, adapted to receive watches or other articles, frames B, to which the hooks are connected, and a flexible backing supporting the frames or hooks, and said hooks A formed with 60 upper hooks, A', adapting them for suspension from a rod or other suitable support, substantially as herein set forth.

7. The combination of a watch-rack consisting of hooks A, adapted to receive and retain 65 watches or other articles, frames B, to which the hooks are attached, a flexible backing or netting to which series of the hooks and frames are attached, and the upper row of hooks having hooks A', and a rod-frame, F G G, and springs 70 or ties, as at I I, connecting the opposite lower corners of the rack to the posts G G, substantially as herein set forth.

JAMES E. GAUSE.
